ANTHONY GUTOWSKI AND THADDEUS S. BLAZUCKI, OF DETROIT, MICHIGAN.

COMBINED MILK AND MAIL BOX.

1,191,589.

Specification of Letters Patent. Patented July 18, 1916.

Application filed March 31, 1916. Serial No. 87,899.

To all whom it may concern:

Be it known that we, ANTHONY GUTOWSKI and THADDEUS S. BLAZUCKI, citizens of the United States, residing at Detroit, county of Wayne, State of Michigan, have invented a certain new and useful Improvement in Combined Milk and Mail Boxes, and declare the following to be a full, clear, and exact description of the same, such as will enable others skilled in the art to which it pertains to make and use the same, reference being had to the accompanying drawings, which form a part of this specification.

This invention relates to combined milk and mail boxes. It is constructed to operate as a container for either milk or mail, but the invention is especially capable of use as a container for articles that have some weight, such as a bottle of milk. When so used, it automatically locks itself when an article of this character is placed within it. Automatic locking containers of this kind are not broadly new. Our invention as regards the milk container, considered apart from the combined mail box and milk container, inheres in the mechanism for automatically locking the door through which the article is placed and also in the double arrangement of latches, one of which is trapped when the locking mechanism is put into operative position by the weight of the article. These features will more fully appear in the description.

In the drawings, Figure 1 is a front elevation, the door being open. Fig. 2 is a vertical section. Fig. 3 is a section of the outside-controllable latch. Fig. 4 is a section of the latch adapted to be trapped by the automatic locking mechanism.

Fig. 1 indicates the casing which may be of various conformations and which is provided at the top with a lid *b* provided with a lock *c*, and this lid is ordinarily kept locked. At the front a door *d* is supported upon hinges and is provided with an outside latch *e* and an inside latch *g*. The outside latch can be operated from the outside by the knob *h*, but the inside latch is trapped to lock the door when the hook *i* is drawn down in registry with the opening *j* in the door jamb. This hook is dropped down in registry with the opening in the door jamb by the depression of the platform *k*. This platform *k* is connected with the bar *l* upon which the hook is carried by means of the jointed elbow *m*. This bar and jointed

elbow reciprocate vertically in the housing *n* on the inside of the casing *a*. The platform is normally held in its upward position and the hook out of the path through the opening *j* by means of the flat spring *o*. However, when the milk bottle is inserted within the casing or any other article of similar weight, the platform *k* is depressed as shown in the dotted lines of Fig. 2. Consequently the hook *i* drops down across the opening *j*. The cam *x* serves to throw the hook over against the inside of the door jamb and hold it there. Hence, when the delivery man slams the door *g* shut, the inner latch *g* is trapped behind the hook *i*. Consequently the door cannot be opened and the contents of the casing can only be taken out by using a key and lifting the lid *b*. Of course, when the article is removed from the platform, the hook *i* is withdrawn from the opening in the jamb and when the door is again grasped, the outside latch may be removed by the knob *h* and the inside latch is not trapped but passes freely through the opening *j* in the jamb. This container may very nicely be also used as a mail box without materially enlarging its cubical capacity. The lid is provided with a slot *p* ordinarily covered by a small hinged cover *q*. Through this slot the mail may be dropped, and inasmuch as there is a partition *r* between the mail compartment and the milk compartment, one cannot reach the mail through the door *d* even when this may be opened. The mail can only be obtained by unlocking the lock *c* and lifting the lid *b*.

An important feature of this combined milk and mail box is that either compartment can be enlarged at the expense of the other compartment when necessary, and consequently the entire container does not have to be as large as if it were simply a case of a box for one kind of articles added to a box for another kind of articles. By the use of the swinging partition *r* which is ordinarily kept in the position shown in the full lines by the spring *s*, the milk compartment may be enlarged as shown in the dotted lines of Fig. 2. The milk bottle will push the partition *r* back to the position shown in the dotted lines, but it will never push it back so far as to bring the partition under or to the rear of the slot *p* so that the mail will drop into the milk compartment. To prevent the milk bottle from so doing, a stop strip *t* is attached to the platform *k* so that the bottle

can never be shoved any farther than this strip, which will not be far enough to push the swinging partition *r* beyond the mail slot *p*. The spring *u* is used at the hinges 5 of the lid *b* to prevent a too sudden and noisy drop of the lid.

What we claim is:

1. An automatic locking receptacle, having in combination, a casing provided with 10 a hinged lid and a swinging door at the side, means for locking the lid, an outside-controlled latch on the swinging door, a second latch unsusceptible to control from the outside adapted to swing through an opening 15 in the jamb, and a latch trap adapted to be drawn across the opening in the jamb by the weight of an article inserted in the casing.
2. An automatic locking receptacle, having 20 in combination, a casing provided with a lid and with a swinging door, means for locking the lid, an outside-controlled latch, a second latch unsusceptible to outside control, a hook adapted to be drawn down in

the path of the second latch to trap the 25 same, a movable platform normally raised, and connections between the swinging platform and the hook to draw the hook down to trap the second latch when an article rests upon the platform.

3. An automatic locking receptacle, having in combination, a casing provided with a lid, means for locking the lid, a swinging door, a door jamb attached to the casing and provided with an opening, a spring-projected latch unsusceptible to outside control and arranged to pass through the opening in the door jamb, a hook or latch trap adapted to be drawn across the opening in the jamb, and a movable platform normally 35 raised and which when depressed by the weight of an article carried thereon draws the said hook or latch trap across the opening in the door jamb.

In testimony whereof, we sign this specification.

ANTHONY GUTOWSKI.
THADDEUS S. BLAZUCKI.
